PARAKEET EXERCISE PERCH

Neil A. Winton, Springfield, and William A. Winton,
West Springfield, Mass.

Application March 1, 1955, Serial No. 491,318

3 Claims. (Cl. 119—26)

This invention relates to parakeet perches and more particularly to a parakeet exercise perch.

Parakeets are fast becoming common household pets and one of the first objectives of the new owner of a parakeet is to teach the parakeet to utter words that will amuse the owner thereof.

It is common knowledge that birds of all types, including parakeets become accustomed to a new environment more readily when they are relaxed. We have found that the parakeet exercise perch described herein assists a parakeet to completely relax himself.

An object of the present invention is to provide an exercising perch which will facilitate getting a parakeet in a cheerful state of mind so as he will talk or chatter more profusely.

A further object of the present invention is to provide an exercising perch on which a parakeet can perform acrobatics for the entertainment of the household possessing said parakeet.

Another object of the present invention is to provide a portable perch for a parakeet which is attractive and appealing to parakeets, so as a householder can conveniently attract a parakeet into a particular room or part of a room by moving the apparatus described herein to a chosen location for the parakeet.

The above and other objects will more clearly appear from the following detailed description of the device, with particular reference to the accompanying drawing, in which:

Fig. 1 is a perspective view of a preferred embodiment of the novel exercise perch;

Fig. 2 is a perspective view of a modified form of the new exercise perch, the same being of integral construction;

Fig. 3 is a perspective view of another modification of the novel exercise perch adapted for attachment to a wall surface; and

Fig. 4 is a similar view of another modification of the new exercise perch which may be used inside a bird cage.

Referring to Fig. 1, a resilient perch member generally indicated by numeral 1, having a diameter of approximately two and one half (2½) inches and having its coils spaced approximately one and one third (1½) inches from each other is vertically supported by a stand 2. It may be made out of relatively light spring wire or a resilient plastic, preferably of brightly colored wire or plastic. The resiliency of perch member 1 is such that when a parakeet alights on any one of the coils, it will bounce up and down, sway with the weight of the bird, and oscillate back and forth.

The diameter of the coils as above noted is sufficient to form a passageway centrally of the longitudinal axis of the coils so that a bird can travel up and down the coils on the inside thereof and the spacing between coils is sufficient to permit the passage of a bird between any of the adjacent windings of the member 1. Preferably all of the adjacent windings of member 1 are vertically spaced to permit passage of a bird.

2

The lower end of member 1 is inwardly turned to form a central ring for attachment of the member in an upright position on the standard 2. The ring may be fastened to the standard as by a bolt and wing nut assembly at 3. At the top of the member 1, the coil is also inwardly turned to form a central ring for attachment of a horizontal rod 4. The rod 4 is transversely supported as by a bolt and nut assembly and if desired bells 5 and 6 may be hung at each of the outer ends.

Fig. 2 shows a modified form of the device of a one piece construction having a resilient coil member generally indicated by numeral 7 which is of similar dimensions and characteristics as member 1, but additionally formed with an integral stand 8 and an integrally formed bar perch 9.

An exercise perch for agile parakeets is shown by Fig. 3. A resilient coil member generally indicated by numeral 10 with similar dimensions and characteristics as member 1 may be vertically supported as against a

wall surface or the like as at 11. The lower end 12 of the perch member 10 extends tangentially of the coil winding and is formed with a bent ring for fixing of the wall. Thus the bottom coil provides an axial opening to the interior longitudinal passage between the coils.

Likewise the upper end 13 of the spring member 10 extends tangentially and outwardly at the opposite side of member 10 to leave the upper end of the coils open for access to the axial passage. The outer end of the coil extension is formed with a bent ring for attaching a horizontally disposed bar perch 14 supported outwardly of the member 10 so as not to obstruct the axial opening at the top.

This embodiment of the invention permits a bird to move axially through the member 10, from below the member 10 to above said member or vice versa.

The perches shown by Figs. 1 and 2 can be used either inside or outside of a bird cage, while the perch shown by Fig. 3 is primarily for use outside a cage. A device specifically adapted for cage use is shown by Fig. 4. A resilient coil perch member generally indicated by the numeral 15 having similar dimensions and characteristics as member 1 is hung from the top of a bird cage. An integrally formed lower bar perch 16 may be formed at the lower end thereof.

The dimensions and resilient characteristics of the perch members 1, 7, 10 and 15 permit a parakeet to alight on any of the coils making up said members, to walk around the outside of the respective coils, to hop from one side of a coil to the other, to hop up or down from one coil to the next and to bounce on each coil. As a parakeet hops around on the device, the coiled member as shown at 1, 7, 10 and 15 will provide an oscillating movement simulating the motion of a branch swinging in the wind.

The embodiment of the present invention shown in Fig. 3 is entertaining to a parakeet possessing the ability to nose dive through a sleeve member. Both ends of member 10 are open, permitting a parakeet to enter the top and dive through the axial passage.

There are numerous other ways in which parakeets can amuse themselves with a device constructed according to the present invention the only limitation being the ingenuity of the individual parakeet.

What is claimed is:

1. An oscillating exercise perch for parakeets comprising a coiled member of resilient spring material, the successive coils of said member being spatially wound and in relaxed condition being in longitudinally spaced relation affording access between adjacent coils for passage of a parakeet therebetween to the interior of said member, the windings of said coils being of a diameter affording a passageway free of obstructions for a para-

keet to pass axially through the interior of said member, supporting means at the base of the member for holding said member in vertically disposed position and a horizontal perch bar affixed to the top thereof, said bar being disposed transversely of the end of said member with the ends of the bar extending beyond laterally opposite sides of the member in overhanging relation.

2. An oscillating exercise perch for parakeets comprising a coiled member of resilient spring material, the successive coils of said member being spatially wound and in relaxed condition being in longitudinally spaced relation affording access between adjacent coils for passage of a parakeet therebetween to the interior of said member, the windings of said coils being of a diameter affording a passageway free of obstructions for a parakeet to pass axially through the interior of said member, supporting means integrally formed with the coil member at the base thereof and a horizontal perch bar integrally formed and disposed transversely at the top free end of said coil member.

3. An oscillating exercise perch for parakeets comprising a coiled member of resilient spring material, the successive coils of said member being spatially wound and in relaxed condition being in longitudinally spaced relation affording access between adjacent coils for passage of a parakeet therebetween to the interior of said member, the windings of said coils being of a diameter affording a passageway free of obstructions for a parakeet to pass axially through the interior of said member, supporting means comprising means at the top of said member for attachment in depending relation and a perch bar formed transversely of said member at the lower end thereof.
